UNITED STATES PATENT OFFICE

165,663

COMBINED MASS CARD HOLDER AND DEPOSIT BOX

McKenzie H. Parent, Tampico, and Arthur V. Skarin, Prophetstown, Ill.; said Skarin assignor to said Parent

Application November 21, 1949, Serial No. 6,172

Term of patent 3½ years

(Cl. D29—23)

To all whom it may concern:

Be it known that we, McKenzie H. Parent and Arthur V. Skarin, both citizens of the United States, residing, respectively, at Tampico, Illinois, and Prophetstown, Illinois, have invented a new, original, and ornamental Design for a Combined Mass Card Holder and Deposit Box, of which the following is a specification, reference being had to the accompanying drawing, forming a part thereof.

We claim:

The ornamental design for a combined mass card holder and deposit box, as shown.

MCKENZIE H. PARENT.
ARTHUR V. SKARIN.
